UNITED STATES PATENT OFFICE.

CHARLES F. SMITH, OF NEW BRITAIN, CONNECTICUT, ASSIGNOR TO LANDERS, FRARY & CLARK, OF NEW BRITAIN, CONNECTICUT.

DESIGN FOR A KNIFE-HANDLE.

SPECIFICATION forming part of Design No. 35,826, dated March 25, 1902.

Application filed December 20, 1901. Serial No. 86,715. Term of patent 7 years.

To all whom it may concern:

Be it known that I, CHARLES F. SMITH, a citizen of the United States, residing at New Britain, in the county of Hartford and State of Connecticut, have invented and produced a new and original Design for a Knife-Handle, of which the following is a specification, reference being had to the accompanying drawings, forming part thereof.

Figure 1 is a side elevation of a knife-handle, showing my design. Fig. 2 is a plan view of the same.

As shown in the drawings, the bolster end of the handle begins with a plain band 3, then a rounded bead 4, both encircling the handle. Adjacent to the said bead 4 there is an ornamental band 5 of considerable width and which is terminated with a rounded bead 6 and plain band 7. The ornaments on the wide band 5 consist, mainly, of scrolls that extend from bead 4 to bead 6 at top and bottom, with shorter scrolls at the sides, as shown.

The body portion 8 of the handle is of an ordinary form. At the butt of the handle there are two top and bottom scroll-bands 9, 25 with a shorter scroll ornament 10 at their confronting ends. The forward ends of the scroll-bands 9 meet the rounded bead 11, in front of which is a plain band 12. At the sides there are shorter scrolls 13 and leaflets 30 14, partly overlapping the bead 11 and band 12, all as shown.

Having described my invention, what I claim as new, and desire to secure by Letters Patent, is—

The design for a knife-handle herein shown and described.

CHARLES F. SMITH.
